UNITED STATES PATENT OFFICE.

TALBOT LENNOX, OF MARSHALLTOWN, IOWA.

SEPARATOR FOR CRUDE OIL AND GAS.

Application filed February 7, 1924. Serial No. 691,164.

To all whom it may concern:

Be it known that I, TALBOT LENNOX, a citizen of the United States, and a resident of Marshalltown, in the county of Marshall and State of Iowa, have invented a certain new and useful Separator for Crude Oil and Gas, of which the following is a specification.

The object of my invention is to provide a separator of simple, durable and inexpensive construction, and of small and compact form, that may be readily, conveniently and economically moved from place to place and set up for use, and by the use of which crude oil and gas delivered from an oil well may be passed through the separator and the gas thoroughly and completely separated from the oil, thus leaving the oil in its best condition for storage in tanks and the like and saving the gas for use.

A further object is to provide improved means for automatically removing the oil and also any water that may be discharged into the separator with the oil, and automatically maintaining a certain pre-determined oil level and water level within the separator.

My invention consists in the construction, arrangement and combination of the various parts of the device, whereby the objects contemplated are attained, as hereinafter more fully set forth, pointed out in my claims, and illustrated in the accompanying drawings, in which:

Figure 1 shows a vertical central sectional view of an apparatus embodying my invention.

Figure 2 shows a detail side view of the exterior illustrating the gas and water discharge pipes and their automatic opening and closing devices partly in section taken on the line 2—2 of Figure 1.

Figure 3 shows a transverse sectional view on the line 3—3 of Figure 1; and

Figure 4 shows a horizontal sectional view taken on the line 4—4 of Figure 1.

Referring to the accompanying drawings I have used the reference numeral 10 to indicate the outer casing of my improved separator, which is preferably made of circular form and closed at both ends, substantially like the casing or outer walls of a steam boiler. Spaced slightly below its horizontal center is a perforated metal partition 11, and contained within the space above the partition is a tubular spiral or

helical separator coil 12 substantially rectangular in cross section and having its lower end open and communicating with the space below the partition 11 at the point 60 marked 13. Its upper end near the top of the casing communicates with the discharge pipe 14. This coil 12 is preferably braced and supported by means of supporting rods 15 secured to the partition 11. 65

Communicating with the interior of the casing at a point above the partition 11 is a pipe 16 which communicates with the flowing or spouting well, or other sources of gas and crude oil supply. Below the partition 70 11 I have fitted to the exterior of the casing a circular flange member 17 having a detachable arched cover member 18. Mounted within this detachable arched cover member are two shafts 19 and 20, each being rotatively supported in packing boxes 21 mounted in the cover member 18. On the shaft 19 within the cover member 18 is a square head 22, and a rounded projection 23 at the end of the shaft extends beyond this square 75 portion. The other shaft 20 is also provided with a square head 24 within the cover member 18, and this part 24 has a depression to receive the projection 23. Fixed to the outer end of the shaft 19 is an arm 25 80 having an adjustable weight 26 therein and fixed to the shaft 20 is a similar arm 27 having an adjustable weight 28.

Communicating with the interior of the casing at a point spaced a considerable distance above the bottom is an oil discharge pipe 29 having a cut-off valve 30 therein controlled by a valve stem 31, and this valve stem 31 is connected to the arm 27. Communicating with the interior of the casing 90 at a point near its bottom is a water discharge pipe 32. This water discharge pipe has a valve 33 therein controlled by a valve stem 34, which latter is connected to a lever 25. 95

Mounted upon the part 24 of the shaft 20 is an arm 35 projected toward the central portion of the interior of the casing and having a cup shaped float 36 at its inner end, and connected to the part 22 of the shaft 19 is a similar arm 37 extended inwardly and then downwardly and also having a cup shaped float 38 on its inner end. In Figure 1 of the drawings, this float 38 is shown adjacent to the water level which 100 is indicated by the numeral 39, and the cup shaped float 36 is shown at the oil level 110

which is indicated by the numeral 40. When in use the weights 26 and 28 are so positioned relative to their respective bars that they will counterbalance their respective cup shaped floats when the latter are full of oil.

In practical use it is obvious that on account of the compactness and relatively small size of my improved separator it may be readily and easily transported and set up. When a pipe is connected to the intake 16 from a flowing or gushing well, then a quantity of mixed gas and crude oil will be forced, under high pressure, into the interior of the casing. This oil and gas will then flow downwardly through the perforated partition as indicated by the arrows in Figure 1. When the oil under pressure passes through the perforated partition, it will be divided into small streams or jets, facilitating the escape of the gas. That is to say, it will be sprayed and the globules of oil will thereby become finely separated so that the gas commingled therewith will be thereby free from the oil. This gas will then pass upwardly through the opening 13 into the spiral separating coil, as indicated by the arrows in Figure 1, and on account of the high pressure of the gas it will flow with great speed through the coil. There will, of course, be more or less oil enter the opening 13 with the gas. However, on account of the centrifugal action to which the oil is subjected during its rapid passage upwardly through the coil, the globules of oil will be thrown out against the outer wall of the coil. In Figure 3 I have indicated the globules of oil forced against the outer wall of the coil by this centrifugal action, and on account of the fact that the coil itself is of large diameter in cross section, the oil will flow back by gravity into the casing below the perforated partition, and during the travel of the oil and gas through the coil, every particle of oil will be separated from the gas before it reaches the discharge point.

In practice I have found that, at the discharge point, a white handkerchief may be placed in front of the gas discharge port and it will not be discolored by the oil. This gas is then conducted through a suitable pipe to a container where it may be utilized.

The oil passing through the perforated partition will be accumulated in the lower portion of the casing, and will maintain the float 36 level full of oil at all times, and the upper surface of this float will at all times be slightly above the oil level in the casing, as shown in Figure 1, on account of the weight 28. When the oil accumulates within the casing above a predetermined level, then the arm to which the weight 28 is attached moves downwardly and opens the

valve 30 and permits a quantity of the oil to discharge until the float 36 again falls below a certain predetermined level, thus elevating its weight 28.

During the operation of a separating device of this character, more or less water will also enter the casing and will seek its level below the oil. The water is automatically discharged in the same manner as previously described in regard to the oil. Hence the entire apparatus is automatic in its action.

I claim as my invention:

1. A separator for gas and oil comprising in combination a casing, means for introducing gas and oil into the casing, and a pipe in the form of a helical coil arranged wholly within the casing and having its lower end open to the interior of the casing to receive gas and oil and having its upper end communicating with a gas discharge pipe, and also having an imperforate outer wall, for the purposes stated. 80 85

2. A separator for gas and oil comprising in combination a casing, means for introducing gas and oil into the casing, and a pipe in the form of a helical coil arranged wholly within the casing and having its lower end open to the interior of the casing to receive gas and oil and having its upper end communicating with a gas discharge pipe, and also having an imperforate outer wall, said coil being angular in cross section. 90 95

3. An improved gas and oil separator comprising in combination a casing, means for introducing gas and oil to the interior of the casing, a partition within the casing below a point where the gas and oil enter it, containing a large number of small perforations designed to produce a spray of oil and gas, and an oil and gas separating pipe communicating with the interior of the casing below the perforated partition and extended upwardly to a point of discharge. 100 105

4. In a device of the class described, the combination of a casing, means for introducing oil and gas into the upper end thereof, means for collecting and retaining a quantity of oil in the bottom thereof, a discharge pipe communicating with the casing, a valve for controlling the discharge pipe, a cup shaped float open at its top and designed to receive the oil that is delivered into the casing and thereby maintained filled with oil during the operation of the device, means for counterbalancing the weight of the float when filled with liquid, means connected with the float for operating said valve to open and close upon movement of the float. 115 120 125

5. In a device of the class described, the combination of a casing, a discharge pipe communicating with the interior of the casing at a point spaced above the bottom 130

thereof, a second discharge pipe communicating with the interior of the casing below the first one, a controlling valve for each discharge pipe, a hollow support secured to the casing and communicating with its interior, two shafts mounted in the said hollow support and extended inwardly to the interior of the casing a float for each shaft, a

counterbalancing means for each float, and means whereby upon movement of either ¹⁰ float the corresponding valve will be operated, substantially as and for the purposes stated.

Des Moines, Iowa, January 31, 1924.

TALBOT LENNOX.
